UNITED STATES PATENT OFFICE.

CHARLES W. BECK, OF ROCKVILLE CENTER, NEW YORK, ASSIGNEE, BY MESNE ASSIGNMENTS, TO MICHIGAN MOTOR SPECIALTIES COMPANY, OF DETROIT, MICHIGAN, A CORPORATION OF MICHIGAN.

TERMINAL CONNECTOR FOR SPARK-PLUGS.

1,072,561.

Specification of Letters Patent. Patented Sept. 9, 1913.

Application filed October 15, 1910. Serial No. 587,151.

To all whom it may concern:

Be it known that I, CHARLES W. BECK, a citizen of the United States, and resident of Rockville Center, county of Nassau, and State of New York, have invented certain new and useful Improvements in Terminal Connectors for Spark-Plugs, of which the following is a specification.

In the drawings: Figure 1 is a side elevation of a spark plug showing my improved terminal connector in position; Fig. 2 a longitudinal vertical sectional view of the connector; Fig. 3 a plan view thereof; Fig. 4 a similar view showing the switch and locking lever in position to lock the connector to the spark plug and open the sparking gap; and Fig. 5 a similar view with the switch and locking lever in position to release the connector from the spark plug. Fig. 6 shows the manner in which the yoke is attached to the socket.

It is the main object of this invention to provide a terminal connector of simple form by means of which it may be readily determined, under ordinary and usual working conditions, whether or not any particular plug is sparking. This is accomplished by providing a terminal with a switch device and a pair of supplemental visible sparking points so that by opening the switch a spark will be visible between the supplemental sparking points if the spark plug is working properly. It will therefore be seen that in order to test any particular spark plug it will only be necessary to open the terminal switch and to observe the supplemental sparking points when cranking the engine. It is manifest that any one of the spark plugs may be tested without detaching the terminal connector from the spark plug.

Another object of the invention is to provide means whereby the connector will be locked to the spark plug terminal when the switch lever is moved to open the sparking gap.

Referring to the various parts by numerals, 1 designates the spark plug which may be of any suitable construction formed with the usual post terminal 2 to which the terminal connector is adapted to be attached.

The terminal connector consists of an insulating block 3 of suitable material, preferably the usual hard fiber insulation. To one end of this insulation block is clamped

a forwardly extending contact plate 4 which carries at its forward end a rigid clamping jaw 5, said jaw being offset from the longitudinal center line of the connector, as shown clearly in Fig. 3, and recessed on its inner edge, as at 6, to receive the post terminal of the plug. The plate 4 is formed at its attached end with integral straps 7 which are clamped around the insulation to secure the plate 4 thereto. Pivoted to the plate 4 at the inner end of the jaw 5 is a companion clamping jaw 8, said jaw being formed with a recess 9 in its inner edge to receive the spark plug terminal. The jaw 8 is adapted to be swung outwardly away from the jaw 7 to release the post terminal, as shown clearly in Fig. 5 of the drawings. The other end, or what might be termed the outer end, of the insulation block 3, is secured between the upper and lower plates of a flat metal yoke 10. The upper plate of said yoke is formed with straps 11 which are adapted to be bent around the insulation block and under the lower plate of said yoke, as shown clearly in Fig. 1, to securely clamp and rigidly hold the insulation block within the yoke. This upper plate of said yoke is also formed with an upwardly and forwardly extending locking lip 12, said lip being cut out of the main body of the plate, thereby forming an opening 13, for a purpose which will be herein-after described. The yoke 10 is attached to a socket 14 in any suitable manner. As shown in the drawing, it is connected by a bar 15 which lies within the yoke, the ends thereof being passed through apertures in the front wall of the socket, said ends being bent over on the inner side of said wall, thereby rigidly and permanently clamping the yoke to said socket.

Pivotaly mounted upon the contact plate 4 is a switch and locking lever 16, said lever being formed with one straight edge 17 and the cam 18 on the opposite side of the pivot from the straight edge 17, said cam being preferably on an arc struck from the center of the pivot. The outer end of this switch lever is formed with a forwardly projecting contact lip 19 which is adapted to overlie the inner end of the contact jaw 8 when the switch lever is arranged parallel with the longitudinal center line of the connector, as shown in Fig. 3. In this position of the

lever the end thereof is approximately in contact with the jaw 8 and locks the same in its closed position and in contact with the spark plug terminal when the device is in position on a spark plug. The other end 5 of the lever extends across the space between the contact plate 4 and the contact yoke 10, and electrically connects said two contact parts. The extreme outer end of the lever 10 in this position is engaged under the contact lip 12 so as to insure a close electrical connection between the yoke 10 and said lever. The lever is provided at one edge 15 with a finger piece 20 by which it may be readily operated.

The adjoining edges of the contact plate 4 and the contact yoke 10 are spaced a suitable distance apart, preferably at such a distance that the current will not, under ordinary 20 conditions, jump across the space between said plates. Each contact part is provided with a central sparking point 21 which approach each other so that if a spark passes from one of said contact plates to the other 25 it will jump across the space between the said two sparking points. It will, of course, be understood that the same result may be obtained by providing only one sparking point. It is manifest that the current will 30 jump across the space offering the least resistance.

The insulation 22 of the terminal wire 23 is fitted within the socket and the wire is passed through an opening 24 in said socket, 35 and then down through the opening 13 in the yoke, the end of said wire being secured to the under side of the yoke, as indicated in Fig. 2. It will, of course, be understood that the terminal wire may be connected to the socket or to the contact yoke 10 in any 40 suitable manner.

When it is desired to test the plug to ascertain whether or not current is properly flowing through the plug the switch lever 45 16 is thrown to the position shown in Fig. 4 so that the cam 18 maintains the contact jaws 8 in its locked position and the two sparking points 21 will be uncovered. This permits it to be readily observed whether or 50 not current passes from one of said points to the other. When it is desired to detach the connector from the spark plug terminal the switch lever is reversed and brought to the position shown in Fig. 5. In this 55 position the straight edge 17 of the switch lever permits the contact jaw 8 to be swung open, thereby releasing the connector from the post terminal.

Having now fully described my invention 60 what I claim as new, and desire to secure by Letters Patent is:

1. A terminal connector comprising a block of insulating material, two contact parts secured thereto and insulated from 65 each other, means carried by one of said parts

for connecting it to a terminal wire, a pivoted clamping jaw carried by the other part and adapted to connect it to a post terminal of a spark plug, a pivoted switch lever carried by one of said parts and adapted to bridge the space between the contact parts to electrically connect said parts, and means whereby the switch lever will lock the pivoted clamping jaw in position. 70

2. A terminal connector comprising a block of insulating material, two contact parts secured thereto and separated from each other, a sparking point carried by one of said parts and projecting toward the other part, means for securing a terminal wire to one of said parts, a switch lever carried by one of said parts and arranged to bridge the gap between said parts, a movable locking means to lock the connector to a spark plug terminal, the switch lever being adapted to bridge the gap between the contact parts, and secure the locking means in its locked position. 80

3. A terminal connector comprising a contact part adapted to be connected to a terminal wire, a contact part adapted to be connected to a spark plug, means for insulating these two parts from each other, means carried by one of said contact parts for attaching the connector to a spark plug terminal, and movable means for bridging the gap between the two contact parts, said means serving to lock the attaching means to a spark plug when it is in position to bridge the gap between the two contact parts. 90

4. A terminal connector comprising a block of insulating material, a contact yoke connected to one end of said block, a socket connected to said contact yoke, a terminal wire connected to said socket and to said yoke, a contact part connected to the other end of said insulating block and provided with a forwardly extending rigid jaw, said contact parts being separated to form a spark gap, a pivoted jaw carried by said contact part, a switch lever pivoted on said contact part and adapted to bridge the gap between the two contact parts and to lock the connector to the spark plug when in its bridging position, said switch lever in one transverse position uncovering the gap between the contact parts and locking the clamping jaws in clamping position, and in the reverse position releasing said clamping jaws. 105

5. A terminal connector comprising a block of insulation, a pair of contact parts connected thereto and separated a suitable distance from each other, one of said parts being formed with a sparking point projecting toward the other part, means for connecting a terminal wire to one of said parts, a switch lever carried by the other part and adapted to bridge the gap between the two 115

contact parts, a clamping lip carried by one of said parts and adapted to engage the end of the switch lever in its bridging position, a swinging clamping jaw carried by 5 the contact part to which the lever is pivoted, a clamping lip formed on the lever and adapted to overlie the swinging clamping jaw, said lever being formed with a cam surface adapted to engage said clamping 10 jaw and hold it in its locked position.

6. A terminal connector comprising two contact parts, means for insulating said parts from each other, a movable clamping jaw adapted to secure the connector to a 15 spark plug terminal, and a locking and bridging device carried by one of said contact parts and adapted in one position to bridge the space between the contact parts and lock the movable clamping jaw against 20 movement and also adapted in a second position to uncover the space between the contact parts and maintain the clamping jaw locked, and in its reversed position to uncover the space between the contact parts 25 and release the clamping jaw.

7. A terminal connector comprising a block of insulation, a yoke secured to and embracing one end of said insulation, a socket secured to the closed end of said yoke 30 by lugs integral with said yoke, an upwardly and forwardly extending locking lip formed on said yoke, a contact plate secured to the other end of the insulation and formed with a forwardly extending rigid terminal 35 gaging jaw, a pivoted jaw carried by said rigid jaw and a switch lever pivoted on said contact plate and adapted to bridge the gap between the yoke and the rear end of said plate, said lever in its bridging position 40 locking the pivoted jaw in position to engage the spark plug terminal.

8. A terminal connector comprising a block of insulation, a pair of contact parts connected thereto and separated a suitable 45 distance from each other, one of said parts being formed with a sparking point projected toward the other part, means for connecting a terminal wire to one of said parts, a switch lever carried by the other part and 50 adapted to bridge the gap between the two contact parts, a swinging clamping jaw car-

ried by the part to which the lever is pivoted, a cam formed on said lever and adapted to engage said swinging clamping jaw to hold it in its locked position when said 55 lever bridges the gap between the two contact parts.

9. A terminal connector comprising a block of insulation, a pair of contact parts connected thereto and separated a suitable 60 distance from each other to form a spark gap between them, means for connecting a terminal wire to one of said parts, two opposed jaws carried by the other contact part and adapted to grip a spark plug terminal 65 between them, one of said jaws being pivoted and adapted to swing outwardly away from the other jaw and a locking means adapted to be moved into engagement with the movable jaw to hold said jaw against 70 outward swinging movement, said locking means being adapted to bridge the gap between the contact parts.

10. A terminal connector comprising a block of insulating material, a contact part 75 connected therewith, a terminal wire connected to said contact part, a second contact part connected to the said insulating block and formed with a forwardly extending rigid jaw, a spark gap being arranged between said two contact parts, a pivoted jaw carried by said contact part and arranged to swing toward and from the rigid jaw, a switch lever pivoted on the contact part carrying the rigid jaw and adapted to bridge 80 the gap between the contact parts and to lock the movable jaw when said lever is in its bridging position, a cam formed on said switch lever, and engaging the movable jaw whereby said lever in one transverse position will uncover the gap between the contact parts and lock the clamping jaws, and in its reverse transverse position uncovering 85 said gap and releasing the clamping jaws. 90

In testimony whereof I hereunto affix my 95 signature in the presence of two witnesses this 14th day of October 1910.

CHARLES W. BECK.
